UNITED STATES PATENT OFFICE.

CHARLES LEPLEY HAYS, OF ELDORA, IOWA.

LOAD-SUPPORTING MEANS FOR CARRYING-WHEELS.

1,093,131.

Specification of Letters Patent. Patented Apr. 14, 1914.

Application filed February 10, 1913. Serial No. 678,011.

To all whom it may concern:

Be it known that I, CHARLES LEPLEY HAYS, a citizen of the United States of America, and a resident of Eldora, Hardin county, Iowa, have invented certain new and useful Improvements in Load-Supporting Means for Carrying-Wheels, of which the following is a specification.

My invention relates to methods of supporting loads on carrying-wheels, and the object of my improvement is to resiliently support a load with its bearing-points approximately above the tread of each carrying-wheel, to thereby both better insure the actuation of the wheel, and to prevent excessive torsional strains on the parts when in use. This object I have accomplished by the means which are hereinafter described and claimed, and which are illustrated in the accompanying drawings, in which:

Figure 1 is an upper plan view of the chassis of a motor vehicle, in which my improved method of supporting the chassis and its load upon the carrying-wheels is shown. Fig. 2 is an elevation of the inner face of one of the carrying-wheels, with parts of the web broken away, to better disclose the inclosed bearing and resilient means for supporting the load. Fig. 3 is a detail view of my improved mounting for a carrying-wheel, showing the wheel in vertical axial transverse section, with a resilient flexible axle connection thereto. Fig. 4 is a detail view of a similar method of mounting a carrying-wheel, the wheel being shown in plan and in horizontal axial transverse section, with a flexible joint connection to the axle, and with an electrically-driven motor adapted to rotate the axle. Fig. 5 is an elevation of the inner face of a carrying-wheel provided with dished spokes, and having my improved method of supporting a load by resiliently connecting the load-bearing structure by means of supporting coiled springs between said structure and the bearing of the axle. Fig. 6 is a plan view of the structures shown in Fig. 5, with the wheel shown in horizontal axial transverse section. Fig. 7 is a vertical axial transverse section of a railway car-wheel having inclosed supporting connections for the structure which bears the load. Fig. 8 is another vertical axial transverse section of a railway car-wheel with its connections to a load-bearing structure, with slightly variant details of structure. Fig.

9 is a plan view of the parts shown in Fig. 8, with the wheel sectioned horizontally, axially and transversely. Fig. 10 is an elevation of the structures shown in Fig. 9, 60 with the inner face of the wheel removed on a line *a*—*b* of Fig. 8.

Similar numerals of reference denote corresponding parts throughout the several views.

Referring first to Fig. 3, which illustrates my invention as practically applied to a wheel of a motor vehicle, the numeral 25 denotes the outwardly-concaved rim of the wheel which contains a pneumatic tire 26. 70 In order to secure a central space for the bearing-connections, I have done away with the usual spokes and connected the outer face of the hub 12 to the inturned edges of an outwardly-dished plate or web 23, whose 75 outer inturned edges are secured to the said rim by means of the bolts 24. The said inturned edges are, however, carried farther and turned toward the axle 9, to form a partial web on the inner face of the wheel, 80 having a central axial opening 40 through which project the axle and other connections to the wheel. This arrangement leaves the whole middle part of the wheel between the opposite faces of its rim open and unobstructed, and also strengthens the wheel by 85 stiffening it.

The stub-axle 9 has its outer end secured to the hollow hub 12 by threads and by the cap-nut 11, and the hub has a cylindrical extension to the left hollowed out to receive the right-hand end of the axle-bearing 10. Anti-friction balls 13 are seated between this cylindrical extension and said bearing, while other anti-friction balls 14 are seated 90 between said bearing and the axle 9. It will be seen, that on account of the method of support of the hub 12 by the outwardly dished web 23, the hub is so located as to lie outside of the line which passes through the centers of the tires 26. This affords space within the wheel for the reception of connections therein between the bearing 10 and the extremities of the frame cross-bars 1 and 2. The upper surface of the bearing 105 10 may be flattened or provided with other seats for the upper half 18 of the leaf-spring shown, said spring being wholly located within the inner space of the wheel and both halves thereof being orificed in line to 110 permit passage therethrough of the oppositely-directed vertical guide-bars 20 and 28.

which have their inner ends connected to said bearing 10 and their outer ends supported by the brackets 19 and 27 respectively, through whose bent-over ends 22 and 30 respectively their ends pass and are secured by the nuts 22 and 31. The guide-bars are approximately vertical in the center line of the wheel-tread.

The extremity of the upper transverse frame-bar 1 is orificed to be pivotally connected with the upper guide-bar 20 above the spring-half 18, while the similar orificed extremity of the lower frame-bar 2 is similarly pivoted on the lowermost guide-bar 28 but rests upon the lower spring-half 29, the latter part of the spring thus resiliently carrying the load, since the upper bar 1 does not bear upon the spring at all. The ends of the bars therefore have a vertical play upon said guide-bars 20 and 28 in use, forming a resilient connection with the bearing and wheel situated within the wheel itself, and thus bringing the imposition of the load to a location where it lies approximately vertically above the tread of the wheel.

I have shown means for shifting said wheel to change its direction of movement relative to the chassis 3. The transverse frame-bars 1 and 2 are connected by vertical braces 4 having medial bearings 5 for the axle-sections 6, the abutting ends of said sections 6 being connected by differential-gearing 7. The outer end of each section 6 has a flexible resilient connection 8 with the inner end of the stub-axle 9, which permits the stub-axle to be shifted in direction as desired by means of its integral arm 15 with pivotal connection to a transverse rack-bar 17, pinions 34 and 38 meshing with said rack-bar to change its direction of movement. Said pinions are supported in bearings in an arm 37 which is pivoted to the frame 3 and which permits up and down movements of the ends of the shafts 35 and 36 on which the pinions are mounted in the vertical spaces between the blocks 33. In Fig. 1 is shown an equivalent means for rendering the axle flexible and for shifting the stub-axles, which comprises the assemblage of intermediate axle-parts 55 with inner axle-parts 74 and with the stub-axles, the said parts being respectively flexibly connected by means of universal-joints 73 and 54 on each side. In the same way as above described, the stub-axles are actuated by means of arms 79 pivotally connected to transverse rack-bars 80, the latter being actuated by pinions 81 and 82 on shafts 83 and 84 respectively, the axle-parts 74 being connected by differential gearing 75 driven by the power-shaft 77 through the media of the pinions 76 and 78.

In Figs. 5 and 6 are illustrated a slightly variant form of my device as applied to the

wheel of a motor vehicle, in which two helical compression-springs 48 and 47 are used, instead of the leaf-springs above described. In this case the spring 48 is coiled about the upper guide-bar 46 and rests upon a plate 43 seated on the top of the bearing 10, while the spring 47 is seated about the lower guide-bar 49 and rests upon the cross-bar of the hangers 45. The cross-bar of the upper pair of supports 44 restrict the play of the frame-bar 1 over the guide-bar 46. The lower frame-bar is similarly pivoted to the guide-bar 49 and rests upon the helical lower spring 47. In this wheel, the outwardly-dished spokes 50 are used, which are secured to the rim 25 and fastened to the hub 12 by means of plates 51 and rivets 52.

In Fig. 4 I show the same arrangement of parts as in Fig. 3, except that the wheel has outwardly-dished spokes 50, which affords a central space for the bearing-connections and except that the stub-axle is shown flexibly connected to another axle-section 55 by means of a universal-joint 54, while an electrical motor 53 is mounted upon the bearing of the stub-axle and adapted to drive the axle separately.

In Fig. 7, I show my method displayed in application to a car-wheel 56. The wheel 56 is cast with an interior hollow with its outer face reinforced thickly at 57 for necessary strength, and its inner face having an axial opening 64 to permit the reception of the bearing 59 and its connections to the load-carrying structure 62 and 61. The connections of said structure to the stub-axle 58 are similar to that already described, the bearing 59 having vertical oppositely-disposed guide-bars 20 and 28 for the spring-halves 18 and 29 and for the frame-extensions 60 and 63, said extensions being supported resiliently within the interior of the wheel as already described. The Figs. 8, 9 and 10 further illustrate this idea as exemplified in use with a car-wheel 56. The detail is different in that a cross-axle 65 is used, and the truck-structure 67 and 69 has plates 66 and 68, above and below respectively which have pivotal connections with the guide-bars 20 and 28, the terminal nuts 70 and 71 of the latter retaining said parts 66 and 68 on the bars. In all these cases the application of the load is approximately in a line running vertically through the tread of the wheel, and which thus lends strength to the structure coupled with ease of government.

Having described my invention, what I claim as new, and desire to secure by Letters Patent, is:

1. In combination, a wheel secured on a rotary spindle, a sleeve-bearing about said spindle, oppositely-directed vertical guide-bars fixed to said bearing, connected springs located respectively above and below said

bearing, the one resting upon the bearing, and the other movable over the under guide-bar, and rigidly connected frame-members, one movable over the upper guide-bar over 5 the upper spring, and the other supported upon the lower spring and movable over the lower guide-bar.

2. In combination, a wheel secured on a rotary spindle, a sleeve-bearing about said 10 spindle, oppositely-directed vertical guide-bars fixed to said bearing and having stops on their upper and lower ends respectively, springs located respectively above and below said bearing, the one resting upon the bearing, and the other mounted on the lower 15 guide-bar, and rigidly-connected frame-members, one slidably mounted upon the upper guide-bar between the stop on the latter and the uppermost spring, and the other supported on the lower spring and 20 slidably mounted on the lower guide-bar between said spring and said bearing.

3. In combination, a wheel secured on a rotary spindle, a sleeve-bearing about said 25 spindle, oppositely-directed vertical plates

fixed to said bearing and having their extremities bent over at a right angle, oppositely-directed vertical guide-bars fixed to said bearing adjacent and parallel to said plates and having their extremities detach- 30 ably secured to the bent-over parts of the latter, connected springs located respectively above and below said bearing, the one resting upon the bearing and orificed to be mounted upon the upper guide-bar, the 35 other being orificed to be slidably mounted upon the lower guide-bar, rigidly-connected frame-bars, the end of one being orificed to be slidably mounted upon the upper guide-bar above the upper spring and the other 40 having its end orificed to be slidably mounted upon the lower guide-bar and supported upon the lower spring.

Signed at Eldora, Iowa this 29th day of Jan. 1912.

CHARLES LEPLEY HAYS.
